UNITED STATES PATENT OFFICE.

CHARLES H. WESTOVER AND GEORGE D. WESTOVER, OF CADILLAC, MICH.

CAR-COUPING.

SPECIFICATION forming part of Letters Patent No. 337,540, dated March 9, 1886.

Application filed November 14, 1885. Serial No. 182,871. (No model.)

To all whom it may concern:

Be it known that we, CHARLES H. WESTOVER and GEORGE D. WESTOVER, both of Cadillac, in the county of Wexford and State of Michigan, have invented a new and Improved Car-Coupling, of which the following is a full, clear, and exact description.

This invention relates to certain new and useful improvements in car-couplings; and it consists in the construction and combination of parts and details, as will be fully described and set forth hereinafter, and then pointed out in the claims.

Reference is to be had to the accompanying drawings, forming a part of this specification, in which similar letters of reference indicate corresponding parts in all the figures.

Figure 1 is a longitudinal sectional elevation of our improved car-coupling, the pin being raised. Fig. 2 is a similar view, the pin being lowered and passed through a link. Fig. 3 is a cross-sectional view of the same on the line $x-x$, Fig. 2.

The draw-head A is in general of the usual construction, and provided with the top and bottom pin-apertures for the coupling-pin B, having the head B resting upon the collar C, formed on the middle of the top cross-piece of the U-shaped frame D, resting on the draw-head near the front end of the same. The side pieces of the said frame D are slotted longitudinally, and through said slots guide-pins D' pass from the sides of the draw-head. Pins E project from the sides of the frame D at the lower ends. The link-lifter bar G is pivoted in a slot in the bottom of the draw-head, and is provided with the fork H at its front end, the said forked part being bent upward, as shown. The link-lifter G is provided with the slot J, and in the same the lower end of the dog K is pivoted, which is provided at its upper end with laterally-projecting guide-lugs L, which project over the curved shoulders M on the inner sides of the draw-head near the top of the draw-head. A short arm, N, projects from the lower end of the pivoted dog K down through the slot J and under the bottom edge of the pivoted plate G. The shaft O is journaled transversely in a recess in the bottom of the draw-head, and is provided at each end with the downwardly-projecting handle-piece P and

with the arm Q, which is inclined downward and to the front, the said arms Q being adapted to strike the pins E on the vertically-sliding U-shaped frame D. A small cam-arm, R, on the transverse shaft O projects over the rear end of the link-lifter plate G.

The coupling-link S is of the usual construction.

The operation is as follows: Before the cars are coupled the pin B is raised and rests on the top of the dog K, as shown in Fig. 1. When the draw-heads come together, the entering link S strikes the dog K and swings the same inward and from under the pin B, which drops and passes through the link S, thus coupling the cars automatically. To raise the entering end of the link, the shaft O is turned in the direction of the arrow a' by means of the arms P or Q, and thereby the cam-piece R presses down the inner end of the link-lifter G and raises the forked end, as shown in Fig. 2. To uncouple the cars, the pin B is drawn up, and when it is raised the upper end of the dog K swings under its lower end and keeps it raised, or the arms Q are swung in the inverse direction of the arrow a' , causing their ends to strike the pins E on the lower ends of the frame D, whereby the said frame is raised, causing the collar C to raise the pin into the position shown in Fig. 1, when the draw-head is ready for coupling. The short curved arm N prevents the dog K from swinging in the direction toward the front end of the draw-head too far.

Having thus fully described our invention, we claim as new and desire to secure by Letters Patent—

1. In a car-coupling, the combination, with the draw-head A, of the frame D, provided with a pin-aperture, the pins E on the sides of the said frame, the shaft O in the draw-head, and the arms P and Q on the same, substantially as herein shown and described.

2. In a car-coupling, the combination, with the draw-head A, of the pivoted dog K, and of the curved arm N on the lower end of the same, substantially as herein shown and described.

3. In a car-coupling, the combination, with the draw-head A, of the link-lifter G, pivoted in a slot in the bottom of the same and having

a forked front end, and of the dog K, pivoted in the said link-lifter, substantially as herein shown and described.

4. In a car-coupling, the combination, with 5 the draw-head A, of the link-lifter G, pivoted in a slot in the bottom of the same, the dog K, pivoted in a slot in the said link-lifter, and of the arm N, projecting from the lower end of the said dog through the slot in the link-lifter, substantially as herein shown and described.

5. In a car-coupling, the combination, with the draw-head A, having the curved shoulders M in its inner sides, of the dog K, pivoted within the draw-head, and provided 15 with the laterally-projecting lugs L at its upper end, substantially as herein shown and described.

6. In a car-coupling, the combination, with the draw-head A, of the vertically-sliding frame D on the same, the link-lifter G, pivoted in a slot in the bottom of the draw-head, and having its front end forked, the dog K, pivoted in the link-lifter, the shaft O in the draw-head, the arms P and Q on the same, the cam-arm R on the said shaft O, the pins E on 20 the frame D, and of the curved arm N on the lower pivoted end of the dog H, substantially as herein shown and described.
